his Attorney.

UNITED STATES PATENT OFFICE.

HARRY W. YOUNG, OF CHICAGO, ILLINOIS.

ELECTRICAL FUSE.

1,165,563.

Specification of Letters Patent. Patented Dec. 28, 1915.

Application filed March 25, 1914. Serial No. 827,068.

To all whom it may concern:

Be it known that I, HARRY W. YOUNG, a citizen of the United States, and a resident of the city of Chicago, county of Cook, and State of Illinois, have invented certain new and useful Improvements in Electrical Fuses, of which the following is a specification.

My invention relates to improvements in electrical fuses, and has for its object an improved fuse of this character which is of simple construction and efficient in operation, and which is arranged to prevent the ready substitution of fusible members of different capacities from that for which the fuse is designed.

The invention consists in the combinations and arrangements of parts hereinafter described and claimed.

The invention will be best understood by reference to the accompanying drawing forming a part of this specification, and in which,

Figure 1 is a side view of a fuse embodying my invention, Fig. 2, an end view of the same, Fig. 3, a view of the opposite end, Fig. 4, a longitudinal section of the fuse member, and Fig. 5, a section taken on line 5-5 of Fig. 4.

The preferred form of construction as illustrated in the drawing comprises an outer tube 6 of insulating material closed at one end by means of a metallic cap 7 and provided at its other end with a metallic sleeve 8 projecting slightly beyond the end of the tube. The cap 7 and sleeve 8 serve as means for effecting electrical connection with the line terminals in the usual manner. An inner tube 9 of asbestos and liquid glass or other insulating material is removably fitted within tube 6 and is closed at one end by means of a plug 10 of porcelain, glass or other readily frangible insulating material which is cemented or cast in said tube. The head 10 is provided with a central conical dovetail recess 11 and a conical metallic contact member 12 is arranged in said recess and secured therein by a wall of cement 13, the arrangement being such that upon

withdrawal of member 12 the wedging action thereof will fracture the head 10 so as to prevent re-use of the inner tube 9. A metallic plate 14 is imprisoned between the corresponding end of tube 6 and cap 7 and carries an inwardly projecting pin 15 fitting the corresponding socket in head 10

and a securing screw 16 is swiveled between plate 14 and the end of cap 7 in position to engage threads in contact member 12 and effect the fracture of head 10 when tightened.

A fuse wire 17 is soldered at one end to contact member 12 and at its other end to a flat metallic strip 18 which is provided with a backwardly turned outer end 19 passing through a notch 20 in the protruding end of sleeve 8 and resting against the outer side of said sleeve, as shown in Fig. 4. A closing disk 21 is fitted within the outer end of sleeve 8 and is provided on one side with a tongue 22 fitting within a suitable opening in the corresponding portion of sleeve 8 and on its opposite side with an angularly turned tongue 23 passing through notch 20 and overlying end 19 of the fusible member. A spring member 24 is secured to the outer side of disk 21 and is angularly turned to overhang tongue 23 and carries a swiveled binding screw 25 adapted to secure the adjacent parts together, tongue 23 being provided with an opening and sleeve 8 with a registering threaded opening, and end 19 with a notch for this purpose, as will be readily understood.

Screw 25 is secured in position by forming an opening through spring member 24 and upsetting the edges of said opening to enlarge the same. Screw 25 is provided with a groove 27 adjacent its head and is passed through said enlarged opening, whereupon the edges of the opening are again upset into said groove, thus effecting a swiveled connection with said screw. By this arrangement it will be observed that the end of the fusible member may be readily secured so as to effect good electrical contact with sleeve 8 and, that screw 25 may be swung to and away from operative position to facilitate such connection, but can never be displaced or lost without breaking spring member 24. To afford further protection, if desired, inner tube 9 may be filled with any of the usual forms of insulating powders, as will be readily understood.

In use outer casing 6 is furnished in permanent form and inner casings 9 are supplied to replace any destroyed by overloading or otherwise. When an inner casing is inserted in an outer casing, the screw 16 is engaged with the socket 12 and tightened to effect good electrical contact with

the fuse strip 17. This ruptures the plug 10 so that when a fuse strip has been once mounted in the outer casing it cannot be readily reused or removed and replaced 5 thus tending to prevent substitution of fuses of improper capacity. This rupture is due to the fact that the inner portion of the socket member 12 is larger than the outer portion and the cement filling 13 is set and 10 hardened so that when the socket member 12 is drawn outwardly by the action of screw 16 the plug 10 is necessarily ruptured and will fall apart upon removal from the casing 9.

15 While I have illustrated and described the preferred form of construction for carrying my invention into effect, this is capable of variation and modification without departing from the spirit of the invention.

20 I, therefore, do not wish to be limited to the precise details of construction set forth, but desire to avail myself of such variations and modifications as come within the scope 25 of the appended claims.

25 Having described my invention what I claim as new and desire to secure by Letters Patent is:

1. An electric fuse comprising a fusible member provided with means for securing each end in circuit, the means at one end being of a destructible nature; and means for securing said fusible member in circuit and destroying said destructible securing means, substantially as described.
2. An electric fuse comprising a fusible member provided with means for securing each end in circuit, the means at one end

being of a destructible nature; and means for securing said fusible member in circuit and simultaneously destroying said de- 40 structible means, substantially as described.

3. An electric fuse comprising a casing; a frangible head at one end of said casing; a threaded contact member embedded in said head and larger at its inner than at 45 its outer end; a fusible member connected at one end with said contact member and provided at its other end with means for connecting it in circuit; and a screw contact member engaging said threaded contact member, substantially as described.

4. An electric fuse comprising an outer tube of insulating material; a metallic cap closing one end of said tube; a screw swiveled in said cap and extending into said 55 tube; an inner tube of insulating material fitting within said outer tube; a frangible head closing one end of said inner tube; a wedge shaped metallic contact member embedded in said head and provided with a 60 threaded socket adapted to receive said screw; a fusible member in said inner tube and connected at one end with said wedge shaped contact; and means for effecting 65 electrical contact with the other end of said fusible member, substantially as described.

In testimony whereof I have signed my name to this specification in the presence of two subscribing witnesses.

HARRY W. YOUNG.
